MARBLE-GAME TRAY

Ernest J. Swimmer, 340 E. 52nd St., New York, N.Y.

Filed July 12, 1965, Ser. No. 86,126

Term of patent 7 years

(Cl. D34—5)

Fig. 1.

Fig. 2.

FIGURE 1 is a perspective view, of a marble game tray showing my new design, with the rear side and the left hand side being of the same form, as the front and right hand side shown in the figure;

I claim:

The ornamental design for a marble-game tray, as shown and described.
